UNITED STATES PATENT OFFICE.

EDWIN FINN, OF ELKHART, INDIANA.

SCREW-DRIVING MACHINE.

SPECIFICATION forming part of Letters Patent No. 710,676, dated October 7, 1902.

Application filed November 15, 1901. Serial No. 82,400. (No model.)

To all whom it may concern:

Be it known that I, EDWIN FINN, a citizen of the United States, residing at Elkhart, in the county of Elkhart and State of Indiana, 5 have invented a new and useful Improvement in Screw-Driving Machines, of which the following is a specification.

My invention relates particularly to screw-holders for screw-driving machines; and my 10 primary object is to provide an effective device for machines of this character which will serve to hold the screws during the operation of driving the same.

My invention is particularly adapted to 15 machines of the character described in Letters Patent No. 587,441, granted to me December 6, 1892, assuming the machine in said patent to be equipped with screw-drivers instead of boring-tools.

20 My invention is illustrated in its preferred form in the accompanying drawings, in which—

Figure 1 represents a fragmental view, in front elevation, of a screw-driving machine 25 equipped with an improved screw-holder; Fig. 2, an enlarged broken sectional view taken as indicated at line 2 of Fig. 1; Fig. 3 a side view of the detached screw-holder; Fig. 4, a sectional view of the same, the section being taken parallel to the side exhibited in Fig. 3; and Fig. 5, a sectional view taken 30 as indicated at line 5 of Fig. 2 and showing how the individual tool-stocks are adjusted on the slotted cross-bar with which they are 35 connected.

The general construction of the machine is described in the above-mentioned patent, and only such a description of the same is given in the present application as is necessary 40 to an understanding of the present invention.

A' represent side frames of the machine; B B', forwardly-projecting guides with which said side frames are provided; C, a slotted 45 cross-bar of the construction described in said patent and which serves to receive a certain member of each of a series of tool-stocks; D, a series of vertical spindles constituting portions of the tool-stocks; E, a series of vertically-disposed journals adjustably connected with the bar C; F, a transverse shaft from which motion is transmitted, through mem-

bers F' F², to the spindles D in substantially the manner described in said patent; G, a vertically-movable work holder or table constructed and operating as described in said 55 patent, and H a series of screw-holders of novel construction.

The sleeves or bearings E pass through blocks a, which fit into the slot of the bar C 60 and have front and rear flanges a' a², which bear upon the horizontal surfaces of said bar. The sleeves are equipped with nuts a³, by means of which the blocks a are clamped to the bar at any desired position. Thus it will 65 be seen that the sleeves E may be adjusted vertically as desired and also may be adjusted transversely of the machine.

Each screw-holder H comprises a body portion b, an offset shank b', and a detachable 70 screw-receiver b². The part b has a vertical perforation b³ and an intersecting inclined perforation b⁴. The part b² has at its upper end a flange b⁵, provided with a right-hand thread which screws into a threaded socket 75 at the base of the body portion b. The part b² is provided with a vertical channel or perforation b⁶, which registers with and forms a continuation of the perforation b³. Said part b² is provided at its base with vertical slots 80 b⁷, through which project springs b⁸, depending from the upper portion of the part b², where they are secured by means of screws b⁹. The lower ends of the springs b⁸ are inclined, as shown in Fig. 4, and the lower end 85 of the slotted receiver or part b² is equipped with a ring b¹², which houses the lower ends of the springs and serves to strengthen the lower end of said receiver b². The holder is supported, through the medium of the shank 90 b', by a vertical strap or rod b¹³, which is rigidly secured to the shank b' and is at its upper end provided with a vertical slot b¹⁰, through which passes a bolt b¹¹, serving to connect said strap with a block a. 95

In operation the screws are introduced into the receiver b² through the channel b⁴ and are supported by the inclined lower ends of the springs b⁸ in proper position to be engaged by the screw-drivers, which enter the 100 perforations b³. Assuming that a screw has been deposited in each receiver by an attendant, the operation of the machine is such that the platform or work-support G is lifted

by cams in the manner described in said patent till the work engages the lower ends of the receivers b^2 , whereupon as the work continues to rise the screw-holders are pressed upwardly, while the screws are rotated by the screw-drivers and caused to enter the approaching work. In a manner now well understood the cams for raising the table G bear a certain relation to the pitch of the threads of the screws and to the rate of rotation of the spindles which are being used, so that the work is caused to approach the screws at such a rate of speed as to prevent unnecessary injury to the grain of the wood. The necessary vertical movement of the holders is permitted by the slotted connection with the bolt b^{11} , and it will be understood that as the holders move upwardly the screws spread the lower ends of the springs b^8 till the screws are permitted to be driven into the work the full length. Should one of the screw-drivers become connected with a receiver b^2 , as by the introduction of a second screw by a careless attendant, the effect is to cause the receiver to rotate with the screw-driver and become disconnected from the upper portion of the holder. This action is permitted by the right-hand screw connection between the receiver and the part from which it depends, it being understood that the screw-drivers are given a right-hand rotation. Inasmuch as the supporting straps or rods b^9 are connected with the adjustable blocks a , the holders are always in proper position to receive the screw-drivers.

35 A machine of the character described equipped with my improved screw-holding device is well adapted to the work of driving the screws in buggy-boxes and to similar work, and it will be understood that the machine itself may be equipped with any desired number of rows of screw-drivers, with any desired number of individuals in a row.

40 Changes in details of construction within 45 the spirit of my invention may be made. Hence no undue limitation is to be understood from the foregoing detailed description.

What I claim as new, and desire to secure by Letters Patent, is—

50 1. In a screw-driving machine, a reciprocable transversely-adjustable screw-receiver provided with screw-engaging means, in combination with a transversely-adjustable rotary screw-driver and a reciprocating work-holder which serves to move said screw-holder through the medium of the work, substantially as and for the purpose set forth.

2. In a screw-driving machine, the combination of a rotary screw-driver, a screw-receiver provided with screw-engaging means, 60 means for simultaneously adjusting said screw-driver and screw-holder transversely of the machine, and a reciprocating work-holder serving to raise said screw-holder as the work is moved toward the screw-driver, 65 for the purpose set forth.

3. In a machine of the character described, a screw-holder comprising, in combination, a reciprocable supporting member provided with a screw-driver-receiving channel and an 70 intersecting feed-channel, a rotary screw-driver, and a detachable screw-receiver having screw connection with said supporting member and equipped with yielding screw-engaging prongs, said screw connection serving to permit unturning through the medium of the screw-driver, substantially as described.

4. In a machine of the character described, a screw-holder comprising, in combination, a 80 supporting member, and a screw-receiver depending therefrom and having right-hand screw connection with said supporting member, substantially as and for the purpose set forth.

85 5. In a machine of the character described, having a rotary spindle and suitable driving means, the combination of an adjustable sleeve or bearing for said spindle and a screw-holder supported from said bearing and adjustable therewith, substantially as described.

6. In a machine of the character described, a screw-holder comprising a normally depressed body provided with a vertical screw-driver-receiving passage and an intersecting 95 feed-channel, an offset reciprocable stem through the medium of which said body is supported, and a screw-receiver provided with yielding screw-engaging prongs, in combination with a rotary screw-driver and a reciprocating work-holder which elevates the screw-holder while feeding the work toward the screw-driver, substantially as described.

100 7. In a screw-driving machine, the combination of a suitable frame, a rotary spindle, 105 an adjustable bearing for said spindle, a screw-holder supported from said bearing and adjustable therewith and movable longitudinally of the bearing, and a reciprocating work-holder, for the purpose set forth.

EDWIN FINN.

In presence of—

A. C. KITTELESON,
ALBERT D. BACCI.
